[57] CLAIM

The ornamental design for a tray with pegs and elastic band to hold objects thereon, as shown and described.

DESCRIPTION

FIG. 1 is a perspective view of a tray with pegs and elastic band to hold objects thereon showing my new design; FIG. 2 is a left side elevation view of the tray portion, the opposite side being a mirror image;

FIG. 3 is a front elevation view of the tray portion, the opposite side being a mirror image;

FIG. 4 is a top plan view of the tray portion;

FIG. 5 is a perspective view of a peg and elastic band portion;

FIG. 6 is a bottom plan view of the tray portion; and,

FIG. 7 is a perspective view of the tray portion.

The tray, peg and elastic band in FIGS. 2-7 are shown separately for clarity of illustration.
